UNITED STATES PATENT OFFICE.

WALTER BEACH JOSLYN, OF YPSILANTI, MICHIGAN.

AUTOMATIC DECARBONIZER.

1,249,412.

Specification of Letters Patent. Patented Dec. 11, 1917.

Application filed October 30, 1916. Serial No. 128,573.

To all whom it may concern:

Be it known that I, WALTER B. JOSLYN, a citizen of the United States, residing at Ypsilanti, in the county of Washtenaw and State of Michigan, have invented certain new and useful Improvements in Automatic Decarbonizers; and I do declare the following to be a full, clear, and exact description of the invention, such as will enable others skilled in the art to which it appertains to make and use the same.

This invention relates to improvements in decarbonizing devices for use in connection with internal combustion engines.

15 The principal object of the invention is to produce a decarbonizer of simple design which will be automatic in its operation, starting and stopping with the starting or stopping of the motor.

20 An additional object is to provide a decarbonizer of unitary construction which may be very easily installed.

25 Still another object is to provide an improved strainer for use with the decarbonizer.

With these and many other objects in view, my invention resides in the novel features of construction, combination and arrangement of parts which will be hereinafter 30 more particularly described and claimed and shown in the drawings wherein:

Figure 1 is a side elevation partly in section of the front end of an automobile showing my improved decarbonizer in operative 35 position thereon;

Fig. 2 is an enlarged view of a portion of a supply tank showing the decarbonizer detached;

40 Figs. 3 and 4 are vertical transverse sections on the planes of the lines 3-3 and 4-4 of Fig. 2.

Fig. 5 is a detail longitudinal section through the improved strainer; and

45 Fig. 6 is a detail perspective view of a portion of the strainer showing the porous material removed.

In the drawings my improved device is shown applied to the intake manifold I of an ordinary internal combustion engine, the 50 manifold preferably being tapped at any suitable point between the engine cylinders and the throttle valve for the insertion of the spray nozzle 1 attached to the end of a pipe 2. Through this means water is supplied to the combustible mixture from the carburetor, said water being turned into

steam by the heat of the combustion of the gases within the engine cylinders. This steam or vapor prevents the formation of carbon and also tends to loosen any old deposits of carbon which have accumulated on the pistons or cylinders. 60

The device comprises a vertically positioned cylindrical casing 3 having its upper end closed as shown at 4, while its lower end is open as at 5 and internally threaded. One side of the casing is provided with a relatively large opening 6, while smaller openings 7 are formed in the sides of the casing at right angles to the opening 6. 70 Disposed within the casing 3 is a transparent glass cylinder 7' open at both ends, the upper end of said cylinder having a watertight connection with the casing by means of a suitable washer 8. The cylinder 7' is 75 forced against this washer 8 by means of a bushing 9 which is threaded in the lower end of the casing 3, an additional washer 8' being disposed between the bottom end of the cylinder and said bushing 9. By this arrangement a sight feed is provided so that the flow of liquid may be readily ascertained.

The bushing 9 is provided with an externally threaded nipple 10, and the pipe 2 85 is connected thereto by means of a union 11. This construction of the several parts of the device allows water or other liquid to flow from the casing to the intake manifold I. 90

This liquid reaches the casing from a suitable supply tank T through a downwardly inclined pipe 12 which has its upper end formed integrally with the upper portion of the casing and at the side opposite the opening 6. This pipe 12 extends within the tank T and has a flange 13 surrounding the same adjacent its ends, said flange being formed integrally therewith and with said casing. From Fig. 4 it will be seen that 95 this flange is curved to conform to the curvature of the side of the tank T to which it is attached by soldering or the like. A web 14 connects the flange and the pipe 12 with the casing so that a very strong yet 100 simply constructed device is provided.

The opening in the pipe 12 communicates with a bore 15 which is formed transversely through the top 4 of the casing. The outer end portion of the bore 15 is enlarged and 110 screw threaded to receive the threaded portion of a valve stem 16, the latter having a

valve 17 formed on its end for engagement with a valve seat to prevent the flow of liquid from the bore 15 to the bore of a nozzle 18, the latter depending from the top 4 within the casing. The nozzle 18 is preferably formed integrally with the top 4 and in order to form the bore thereof a hole is bored through said top 4, this being later closed by the screw or other form of plug 19. The top 4 is further provided with a threaded opening to receive a set screw 20 which holds the valve stem 16 in adjusted positions in its bore.

From the inner end of the pipe 12 extends a tube 21, the lower end thereof terminating adjacent the bottom of said tank T and provided with a strainer through which the water passes into said pipe.

As soon as the engine is started the vacuum created in the intake manifold will automatically suck the fluid from the tank T through the strainer formed on the end of the tube 21, up said tube and the pipe 12, from whence it flows through the nozzle 18 into the casing, the pipe 2 conveying the liquid from the casing to the manifold. As soon as the suction is suspended, the operation of the device will be stopped. Any suitable liquid may be used in the tank T, but water has been found to work very satisfactorily since the steam which is created therefrom will very readily soften the carbon within the cylinders and prevent the formation of new carbon. In cold weather a quantity of alcohol may be added to the water in the tank to prevent its freezing. The device may be further used as an engine

primer by substituting gasoline for the water within the tank. From the foregoing description it will be obvious that I have invented an extremely simple device, easy of application, which can be manufactured at a slight cost, and yet which will be very efficient in operation.

I claim:

The combination of a tank having an aperture in its side, a casing having a downwardly inclined integral portion extending through said aperture, said casing having an open bottom, an aperture in its side, and a transverse bore extending through its upper end, said bore being decreased at its inner end to provide a valve seat, a valve in the outer end of said bore to coact with said seat, a downwardly inclined pipe secured to said integral extension and having its upper end communicating with the inner end of said transverse bore, the lower end of said pipe terminating adjacent to the bottom of said tank, a transparent cylinder in said casing, said cylinder to form in connection with the opening in the casing a sight feed, a nozzle depending from and integral with the top of the casing within said transparent cylinder, and a connection between the open bottom of the casing and the intake manifold of an internal combustion engine.

In testimony whereof I have hereunto set my hand in the presence of two subscribing witnesses.

WALTER BEACH JOSLYN.
